DRIVE-CHAIN.

959,047.

Specification of Letters Patent.

Patented May 24, 1910.

Application filed December 16, 1909. Serial No. 533,423.

To all whom it may concern:

Be it known that I, WARREN J. BELCHER, a citizen of the United States of America, residing at Hartford, in the county of Hartford and State of Connecticut, have invented new and useful Improvements in Drive-Chains, of which the following is a specification.

This invention relates to drive-chains of 10 that type in which one of the link elements consists of oppositely disposed side-plates and non-rotatable pivot pins extending through the side-plates near the ends thereof, the other link element consisting of oppositely disposed side-plates like the first but having bushings extending through the plates near the ends thereof, the length of the bushings being equal to the width of the links, the pins of said first named links extending through the bushings of said second named links, these links being alternately arranged end to end by passing the pins of one link through the bushings of the other to constitute a chain; certain other link 25 members, to be referred to further on, are embodied in the chain construction, but it is sufficient for the present purpose to state that the link elements being constructed as above described, it would obviously be impossible to separate the chain at any point 30 without driving out one pin and one bushing.

The object of the present invention is to provide means for effecting the separation of a chain of the above described type at 35 some point in the length thereof conveniently and quickly, and without the use of special tools.

The invention is illustrated in the accompanying drawings, in which,—

40 Figure 1 is a sectional plan view of a part of a chain of the type above referred to, the plane of the section being substantially on the axis of the pivot-pins, certain parts thereof embodying the invention being shown in separated relation to the chain. Fig. 2 is a side elevation of the complete chain showing that side thereof to which the retaining clip is attached to the pivot-pins. Fig. 3 is a side elevation like Fig. 2 which 50 shows the retaining clip in another position to illustrate the manner of its application to or removal from the ends of the pivot-pins.

The chain to which the application of 55 this invention is necessary to easily effect

its separation at some point thereof is made up of pivotally united link elements one of which consists of the side-plates *a* which are oppositely disposed and connected together by pins *b* which are non-rotatably secured in the side-plates *a* near the ends of the latter, this non-rotatable connection being attained by flattening one side of that portion of the pins that extends through the plates,—said flattened portion being indicated by *c*. The second link element consists of the side-plates *d* oppositely disposed one to the other and having bushings *e* therein extending through the plates at or near the ends thereof and being non-rotatably secured in said side-plates. These two link elements are connected together end to end in overlapping relation, as shown in Fig. 1 particularly,—that one of the links consisting of the side-plates *d* and the bushings *e* fitting in between the two side-plates *a* of the other link with the pins *b* of said other link extending through said bushing, the pins *b* being preferably headed over to secure them in the side-plates.

A glance at this construction, as illustrated in Fig. 1, will make apparent the difficulty of separating a chain so constructed, and as stated, to overcome this difficulty, is the object of the present invention. This is accomplished by means of a removable link comprising the side-plates *a* and the pins *b* shown in Fig. 1 as separated from the rest of the chain, the pins being secured by one end in one of said plates permanently, means being provided for removably securing the other side-plate *a* to the opposite end of said pins, and in the provision of means to secure the bushing *e* through which the pin *b* extends to one of the pins above referred to, to the end that when said side-plate *a* is removed from the chain one pin *b* will be withdrawn with it from a bushing *e* while the bushing through which the other pin extends will be secured to it in a manner to effect the withdrawal of the bushing with the pin, as it is only by the withdrawal of one of the bushings that a separation of the various elements comprised in the two links can be effected. All of the bushings, except the one which is withdrawn from the chain on the pin *b* just described, are non-rotatably secured in the side-plates *d*, the bushing which is withdrawn with the pin *b* however is removably fitted into the plate *d*,

2
and said bushing may be secured to the pin
b in any suitable manner which will not ob-
struct its free rotation thereon. A desirable
manner of securing the bushing on the pin
5 is shown in Fig. 1, and it consists in fitting
a thin washer f over the end of the pin
tightly, which washer will bear against the
end of the bushing to retain the same in
proper position on the pin. Preferably, the
10 end of the bushing is counterbored, as shown
at g, to receive the washer.

In the drawings, all of the bushings e
have been shown as made in two parts, each
15 of which extends from one of the side-plates
to the longitudinal center line of the chain.
This feature, however, has no relation to this
invention and the bushing may be made
either as shown herein or as consisting of
20 one piece extending from one side-plate to
the other, as desired. When that portion of
the link shown in Fig. 1 is placed back in
position in the chain, the free ends of the
two pins b will extend beyond the outer sur-
25 face of the plates d far enough to permit
immediately under the removable side-plate a,
shown in Fig. 1, and still leave room on the
ends of the pin for the application of a re-
taining clip, such as is shown in section im-
30 mediately under the removable side-plate a.
Fig. 1, this clip being indicated as a whole
by h. The clip is also shown in a locked
position on the pins b in Fig. 2, and in un-
locked position in Fig. 3.

Any type of a locking clip or retaining
35 clip may be used instead of the one shown,
for the invention does not require the ap-
plication of any particular type of clip to
make it operative, it being only necessary to
use a device which shall retain the remov-
40 able plate a in position after it has been ap-
plied to the free end of the pins d of the re-
movable link.

The retaining link shown herein com-
prises one member m which is forked at one
45 end to enter a circumferential groove o in
one of the pins, the other end of said mem-
ber having an opening p adapted to slip
over the top of the other removable pin b
thereby locking in position a second forked
50 member q pivotally connected to the mem-

ber m at r, this forked member q fitting a
groove o in the other pin d in the same
manner as that described in connection with
the member m.

To supplement the side-plates a and the 55
side-plates d of the two links of the chain,
a number of link members s and t are em-
ployed which are substantially coextensive
with the plates a and d, these link members
being preferably arranged in alternate rela- 60
tion one to the other; that is the link mem-
bers s being fitted over the bushings through
which both of the pins of the same side-
plates a extend; whereas, the link members
t, alternating with the members s and ex- 65
tending in opposite directions thereto, fit
over the bushings through which the adja-
cent pins of separate links extend. In
other words, we may assume that the side-
plates a and the pins b constitute one link 70
element, and the side-plates d and the bush-
ings e constitute link elements which con-
nect together the others and the link mem-
bers s and t are so distributed as to be
equally divided between the links which 75
comprise the side-plates a and the links
which comprise the side-plates d.

What I claim, is:—

A drive-chain consisting of links comprising
80 oppositely disposed side-plates and non-
rotatable pins extending through the side-
plates near the ends thereof, and other links
comprising oppositely disposed side-plates
and non-rotatable bushings extending 85
through the plates near the ends thereof, a
pin of one of said links extending through
a bushing of the other link to constitute a
chain, one of the side-plates having the pins
secured therein, being separable from its 90
opposite side-plate, and one of the bushings
of the other link being secured to one of the
pins in said separable plate whereby the re-
moval of said plate will withdraw one
bushing from the chain to permit the separa- 95
tion of the latter.

WARREN J. BELCHER.
